CLAIM

I claim the ornamental design for a display screen or portion thereof with graphical user interface icon, as shown and described.

DESCRIPTION

This patent contains at least one drawing executed in color. Copies of this patent with a color drawing will be provided by the Office upon request and payment of the necessary fee. FIG. 1 is a front view of a display screen or portion thereof with graphical user interface icon showing a first embodiment of the design; and,

FIG. 2 is a front view of a display screen or portion thereof with graphical user interface icon showing a second embodiment of the design.

The broken lines shown are included for the purpose of illustrating the display and portions of the graphical user interface and form no part of the claimed design.

**1 Claim, 2 Drawing Sheets
(1 of 2 Drawing Sheet(s) Filed in Color)**

Related U.S. Application Data

a continuation-in-part of application No. 29/632,350, filed on Jan. 7, 2018, now Pat. No. Des. 857,726.
